ROCKING FIGURE TOY

Bayard C. Reed, Chicago, Ill.

Application October 3, 1950, Serial No. 188,214

7 Claims. (Cl. 46—147)

1

My invention relates to a novelty toy device and has for its object the provision of a toy which may be in the representation of any suitable character or figure and which when moved in a straight line alternately in opposite directions is caused to create the illusion of the toy device alternately reversing positions without actually turning around, thereby providing a high degree of amusement and interest.

Another object of my invention is the provision of a device of the foregoing character which is simple in construction, economical to manufacture, and durable in service.

Other and further objects and advantages of my invention will become apparent from the following description when considered in connection with the accompanying drawings in which:

Fig. 1 is an elevational view of a toy in accordance with my invention.

Fig. 2 is a bottom plan view thereof.

Fig. 3 is a perspective view of a modified embodiment showing the component parts in separated relation, and

Fig. 4 is a view similar to Fig. 2 showing the parts in a different relative position but showing another modified embodiment of my invention.

Referring to the drawings, particularly to Figs. 1 and 2, my invention comprises a base or body portion 10 in the form of a channel member open at each end. The bottom 11 of the base 10 has a cut-out 12 medially thereof substantially as shown. The side walls 13 and 14 of the base are embossed, symmetrically with respect to the transverse axis of the base 10, so that the forward and rearward ends of the said walls are exactly alike in appearance. Each of the side walls 13 and 14 is perforated as at 15 to receive a chain 20 which serves to pivotally support a rocking member shown more clearly in Fig. 3 and indicated generally by the numeral 17, the chain also serving as a means by which the device may be carried as a pendant or in any other manner. The said rocking member comprises two heads 18 and 19 oppositely directed and symmetrically disposed with respect to a transverse bore 21 through which is passed the chain 20. The lower portion of the rocking member 17 is enlarged and is provided with an arcuately shaped bearing surface 23 which preferably is serrated or knurled, the radius of curvature of the said arcuate surface having its center at the axis of the transverse bore 21. As will be apparent, the chain 20 serves as a shaft to pivotally support the member 17.

As will be seen clearly by reference to Figs. 3

and 4, the heads 18 and 19 are identical in configuration, each head in this instance being the caricature of a Scotch terrier. Preferably, the heads 18 and 19 are somewhat grotesquely formed so that certain features thereof may be exaggerated or otherwise altered in order that they may be used advantageously to depict or represent another portion of the body. For example, in the embodiment illustrated in the drawings, the ears 18a of the head 18 in the position, illustrated in Fig. 1, represent the tail of the object.

As will be clearly seen by reference to Figs. 1 and 4, the arcuate surface 23 of the rocking member 17 extends below the plane of the bottom 11 of the base 10 so that when the device is resting on a supporting surface 25, the surface 23 of the member 17 is in direct contact with the supporting surface. The serrations on the arcuate surface 23 enhance the gripping action between the said surface and the supporting surface, thereby assuring rocking of the member 17 in a direction opposite to the direction of movement of the body 10 substantially to the limit of its rotation, so that one head such as 19 is in upright position and the other head 18 is recessed between the walls 13 and 14 substantially as shown in Fig. 1 with only the ears 18a exposed to represent a tail. When the body 10 is shifted in an opposite direction, the rocking member 17 is caused to be rocked so as to present the head 18 for view and the head 19 is then disposed between the side walls of the base member 10 with only the ears 19a exposed. Thus, it will be apparent that upon reciprocation of the body 10 while it is positioned on a supporting surface, the device may be made to change directions alternately. It will be apparent that the embossings on the side walls of the base 10 are of such character as to carry out the caricature or representation of the forward and rearward ends of the animal being depicted as in the present embodiment, a Scotch terrier.

In the embodiment illustrated in Fig. 3, the base 10 is provided with inwardly directed stub shafts which are received in the bore 21 of the member 17 and which pivotally support the member 17. The base is otherwise identical with that shown in Fig. 1 and corresponding numerals are employed to indicate corresponding parts.

In the embodiment illustrated in Fig. 4 a web portion 26 is provided between the heads 18 and 19 of member 17, the said web portion having a perforation to receive a chain similar to the chain 20 from which the device may be suspended, as in the nature of an ornament worn on a

watch or key chain or as a locket worn around the neck. The base is identical with that shown in Fig. 3.

While the toy is shown as in the configuration or representation of a Scotch terrier, it is to be understood that my invention is applicable to other characters and figures.

I claim:

1. A novelty toy device comprising a base member having a bottom and side walls, said bottom having an opening therein substantially intermediate its ends, a rockable member pivotally mounted between said side walls, said rockable member having an arcuate bottom portion projecting through said opening and engageable with a supporting surface, said rockable member bearing two figures arranged substantially symmetrical relative to the pivotal axis thereof, said device when shifted in a straight line in alternate directions effecting alternate rocking of said rockable member so as to present alternately one of said figures.

2. A novelty toy device comprising a base member having a bottom and side walls, said bottom having an opening therein substantially intermediate its ends, said side walls having forward and rearward ends symmetrically formed and simulating the body of an animal, a rockable member pivotally mounted between said side walls, said rockable member having an arcuate bottom portion projecting through said opening and engageable with a supporting surface, said rockable member bearing two figures each simulating the head of an animal and arranged substantially symmetrical relative to the pivotal axis thereof, said heads being complementary in configuration to said side walls, said device when shifted in a straight line in alternate directions effecting alternate rocking of said rockable member so as to present alternately one of said figures.

3. A novelty toy device comprising a base member having a bottom and side walls, said bottom having an opening therein substantially intermediate its ends, a rockable member pivotally mounted between said side walls, said rockable member having an arcuate bottom portion projecting through said opening and engageable with a supporting surface, said rockable member bearing two figures arranged substantially symmetrical relative to the pivotal axis thereof, said device being adapted for straight linear movement in alternate directions so as to rock said rockable member to present alternately to view one of said figures and thereby to effect alternate reversals in the direction assumed by said device without reversing the position of said base member.

4. A novelty toy device comprising a base member having a bottom and side walls, said bottom having an opening therein substantially intermediate its ends, a rockable member pivotally mounted between said side walls, said rockable member having an arcuate bottom portion projecting through said opening and engageable with a supporting surface, said side walls having forward and rearward ends symmetrically formed and simulating the body of an animal, said rockable member bearing two figures each simulating the head of an animal and arranged substantially symmetrical relative to the pivotal axis thereof,

said heads being complementary in configuration to said side walls, said device being adapted for straight linear movement in alternate directions so as to rock said rockable member to present alternately to view one of said heads and thereby to effect alternate reversals in the direction assumed by said device without reversing the position of said base member.

5. A novelty toy device comprising a base member having a bottom and side walls, said bottom having an opening therein substantially intermediate its ends, a rockable member pivotally mounted between said side walls, said rockable member carrying two identical figures each simulating the head of an animal with the heads being directed in opposed relation, said rockable member having an arcuate bottom portion projecting through said opening and engageable with a supporting surface, said side walls having forward and rearward ends symmetrically formed and simulating the body of an animal, said device being adapted for straight linear movement in alternate directions so as to rock said rockable member to present alternately to view one of said heads and thereby to effect alternate reversals in the direction assumed by said device without reversing the position of said base member.

6. A novelty toy device comprising a base member having a bottom and side walls, said bottom having an opening therein substantially intermediate its ends, a rockable member pivotally mounted between said side walls, said rockable member having an arcuate bottom portion projecting through said opening and engageable with a supporting surface, said rockable member bearing two figures arranged substantially symmetrical relative to the pivotal axis thereof, said device when shifted in a straight line in alternate directions effecting alternate rocking of said rockable member so as to present alternately one of said figures, and thereby to effect alternate reversals in the direction assumed by the device without reversing the position of said base member.

7. A novelty toy device comprising a base member having side walls and means connecting said side walls in spaced relation, a rockable member pivotally mounted between said side walls and having a bottom portion engageable with a supporting surface, said rockable member bearing two figures arranged substantially symmetrical relative to the pivotal axis thereof, said device when shifted in a straight line in alternate directions effecting alternate rocking of said rockable member so as to present alternately one of said figures and thereby to effect alternate reversals in the direction assumed by the device without reversing the position of said base member.
